(57) **CLAIM**

The ornamental design for a scooper, as shown and described.

DESCRIPTION

FIG. 1 is a top perspective view for a first embodiment of the scooper, showing the new design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof;

FIG. 8 is a back view thereof;

FIG. 9 is a perspective view of the first embodiment scooper in one non-limiting use showing the scooper being used to remove content out of a container;

FIG. 10 is a perspective view of the first embodiment scooper in one non-limiting use showing the scooper being used to pour scooped content into a glass or cup;

FIG. 11 is a perspective view of the first embodiment scooper in one non-limiting use showing the scooper being used to pour scooped content into a sports bottle or other container;

FIG. 12 is a top perspective view for a second embodiment of the scooper, showing the new design;

FIG. 13 is a bottom perspective view thereof;

FIG. 14 is a top view thereof;

FIG. 15 is a bottom view thereof;

FIG. 16 is a right side view thereof;

FIG. 17 is a left side view thereof;

FIG. 18 is a front view thereof;

FIG. 19 is a back view thereof;

FIG. 20 is a perspective view of the second embodiment scooper in one non-limiting use showing the scooper being used to remove content out of a container;

FIG. 21 is a perspective view of the second embodiment scooper in one non-limiting use showing the scooper being used to pour scooped content into a glass or cup; and,

FIG. 22 is a perspective view of the second embodiment scooper in one non-limiting use showing the scooper being used to pour scooped content into a sports bottle or other container.

The broken lines in FIGS. 9-11, and 20-22 form no part of the claimed design.

1 Claim, 8 Drawing Sheets
